UNITED STATES PATENT OFFICE.

VICTOR K. SAMUELSON, OF CHICAGO, ILLINOIS.

DESIGN FOR A LAMP.

Application filed October 16, 1925. Serial No. 15,149. Term of patent 3½ years.

To all whom it may concern:

Be it known that I, VICTOR K. SAMUELSON, a citizen of the United States, residing at Chicago, in the county of Cook and State of Illinois, have invented a new and ornamental Design for Lamps, of which the following is a specification, reference being had to the accompanying drawing, forming a part thereof.

The drawing shows my improved design in side elevation.

I claim:

The ornamental design for a lamp as shown.

In witness whereof, I hereunto subscribe my name this 14th day of October A. D. 1925.

VICTOR K. SAMUELSON.
